CURTAIN OPERATING MEANS

William C. Raaspe, Omaha, Nebr.

Application March 15, 1937, Serial No. 130,892

1 Claim. (Cl. 156—21)

This invention relates to curtain operating means and more particularly to means for the support and operation of stage curtains. The objects of the invention, broadly, are to provide improvements in the track, the use of axle-mounted double rollers and traction therefor, noiseless movements of the hangers when the curtains are moved, and maintenance of the hangers in vertical planes midway between the double rollers. The invention also includes a primary roller of such construction that lateral or longitudinal movements may be avoided, and includes stabilized mountings for the pulleys.

Minor objects include the use of parts which may be conveniently manufactured, disassembled, and will be practical in operation.

The invention consists of the new and useful construction, combination and arrangement of parts as described herein and claimed, and as illustrated in the accompanying drawing, it being understood that changes may be made in form, size, proportions and minor details as found to be of advantage, said changes being within the scope of the invention as claimed.

In the drawing, Fig. 1 is a view of the invention in side elevation, the curtain being broken away.

Fig. 2 is a side view of the single primary hanger and Fig. 3 is an end view of the same. Fig. 4 is a sectional view, on an enlarged scale, of one of the roller bearings employed.

Referring now to the drawing for a more particular description, I provide a horizontal, rectilinear track 15 adapted to be supported by chains or other flexible elements 16 to a ceiling or other overhead structure, said track being adapted to support rollers 20 moving thereon, each roller 20 being provided with a downwardly projecting arm or hanger 22.

Numerals 25 indicate buffer elements preferably consisting of short sections of rubber hose or elastic tubing each section 25 being secured to an arm or hanger 22 to permit a cable or pull-rope 26 to move freely therethrough, the length of each elastic buffer-section being greater than the diameter of a roller 20, so that when the curtain is drawn to closed position the wheels or metallic parts of one hanger will not strike against the metallic parts or wheels of an adjacent hanger and objectionable shocks and noise may be avoided.

Numerals 27 indicate swivel-hooks which may be detachably mounted in apertures which are formed in the lower ends of the arms 22 for supporting the curtain 28, said swivel-hooks hav-

ing a connection with suitable fasteners 29 which are secured to the curtain, and since each fastener 29 and swivel will be disposed in a vertical plane, any swinging movement of the curtain due to any cause, will be resisted.

The fasteners 29 for the curtain are disposed at uniform distances apart, and the cord or pull-rope 26 slidably engages in the tubular sections.

The single primary hanger is indicated at B (Figs. 2 and 3) and consists, in part, of four wheels 20' arranged in pairs, the wheels of each pair being the same in all respects as the wheels or rollers 20 of the secondary hangers. The axles for the primary hanger are indicated at 21', and each axle 21' is provided midway between its ends with an arm 22'.

These arms 22' are provided between their ends with recesses 23' for receiving the pull-rope 26, and are provided with eyes 24' at their ends for receiving swivel-hooks 27, staples 30 being used for securing the arms 22' to the pull-rope.

It will be noted that each arm 22' and the pull-rope 26 are disposed in a vertical plane, said plane being in line with points on the axles midway between the pairs of wheels or rollers 20' which, together with the fact that four wheels are used, provides a construction of great advantage for operation. Since this primary hanger must sustain severe stresses, especially when the curtain is moved to closed or folded position, it must be provided with an adequate base to prevent undulating movements either longitudinally or transversely of the track, and for that reason the axles 21' and the coupling-strip 31 which connect the two arms 22' are of adequate length.

By referring to Fig. 2 of the drawing it will be seen that the lower end-portions of the arms 22' are disposed outwardly inclined relative to each other so that the end-portion of the curtain, during operation, may be under suitable control, the distance apart for the eyes 24' being greater than the distance from each other of the axles; and as shown in Fig. 1, it will be seen that the hanger B is of such proportions that the folds for the curtain 28 may be spaced apart at uniform distances if desired. Numeral 32 indicates the primary pulley, which is axially mounted at 33.

As shown in Fig. 1 of the drawing, a spacing means is employed consisting of flexible strands 44, each disposed between and attached at its ends to two adjacent arms 22 of the hangers, each strand being of lesser length than the distance apart of two adjacent fasteners 29, this feature tending to cause a wavy condition of 55

the curtain and avoiding a flat appearance.

The ball or roller bearing best shown in Fig. 4 consists of an outer bearing-ring 50, an inner bearing-ring 51 and balls or rollers 52 between said rings, these parts being confined as a complete unit, indicated at C by an annular cap 53 which covers the periphery and one end of the bearing-rings 50 and 51 and also covers the annular slot 54 at one side of said unit, that part of the slot 54 at the opposite side of the unit being uncovered; and at 55 is indicated the opening in the inner bearing-ring for receiving the end of an axle.

Numeral 56 indicates a bracket intermediate the ends of the track 15 upon the top and centrally thereof, and secured thereto by keepers 57, and any suitable number of such brackets may be used, depending upon the length of the track,

and since these brackets are disposed midway between the sides of the track the movable parts will normally be disposed in operative position to resist swinging movements.

I claim as my invention:

In operating means for a curtain provided in spaced relation with upwardly projecting fastening devices, the combination with a track, the roller-bearing hangers supported by the track and having arms attached to said fastening devices, and the pull-rope for moving the hangers to dispose the curtain in extended position, of a plurality of spacing-strands carried by the arms of the hangers to dispose said arms at lesser distances from each other than the distances apart of said fastening-devices to cause the formation of folds when the curtain is extended.

WILLIAM C. RAAPKE.
